(57) **CLAIM**

The ornamental design for a pet toy, as shown and described.

DESCRIPTION

FIG. 1 is a perspective view of a pet toy of the present invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is another perspective view thereof, but shown in a position of use; and,

FIG. 9 is another perspective view thereof, further shown in a position of use.

The broken lines shown in FIGS. 8 and 9 showing an interlocking pet toy illustrates environmental structure. All other broken lines illustrate portions of the pet toy. The broken lines form no part of the claimed design.

1 Claim, 5 Drawing Sheets
